UNITED STATES PATENT OFFICE.

JOSEPH E. MOONEY, OF BALTIMORE, MARYLAND.

SELF-CLOSING VALVE FOR FAUCETS.

SPECIFICATION forming part of Letters Patent No. 252,790, dated January 24, 1882.

Application filed May 24, 1881. (No model.)

To all whom it may concern:

Be it known that I, JOSEPH E. MOONEY, a citizen of the United States of America, residing at Baltimore, in the county of Baltimore and State of Maryland, have invented certain new and useful Improvements in Self-Closing Valves for Faucets; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to improvements in that class of faucets and similar articles wherein are used automatic-closing valves; and its object is to provide a faucet actuated in stopping the flow by the utilization of the pressure of the liquid on the piston-head above the valve or above the valve-seat.

My invention consists in a faucet provided with a piston-head and valve closed by liquid-pressure applied through an induction-way opening in a chamber above the piston-head.

My invention further consists in the novel construction and combination of the parts, as will be hereinafter more fully set forth and specifically claimed.

Figure 1 is a longitudinal sectional view, and Fig. 2 is a sectional view taken through line *x x* of Fig. 1.

The letter A represents my improved faucet, consisting of the bit A', tail A², vertical chamber or cylinder B, the cap C, induction-way D, valve-seat E, formed with the port F, and the induction-way G.

The chamber B is cast annular and subsequently bored to a true circle, in order that prompt and unimpeded action of the piston-head may be secured. It is made of smaller diameter than the head of the faucet for the purpose of forming between its wall and the wall of the faucet the induction-way G. In this chamber is fitted the piston-rod *a*, provided with the head *b*, suitably packed, and having the rod extending beyond the head, and formed with the valve *c*. The faucet is covered with the cap C, which is screwed over the head of

the faucet and formed with a hole in the center to admit the piston-rod. On the under side of this cap is fitted rubber packing *d*, which sets on the top of the walls of the head of the faucet, and is formed with the downward-extending lips *e*, which are pressed against the rod by their own compression, aided by the action of the water. The cap, being screwed down to its place, clamps the packing tight between its lip and the top of the wall of the head of the faucet, and thus secures it firmly in place.

The upward movement of the piston is effected by pressure on a lever, *H*, suitably fixed to the projecting end of the piston-rod and cap of the faucet. To further prevent the escape of water through the hole in the cap the piston-rod has bushing fitted around it at *f*.

The induction-way D, leading into the cylinder B, extends around the chamber until the wall of the faucet intercepts and combines with the wall of the cylinder at the front of the faucet, where they are identical. In other words, the passage-way D is eccentric to the chamber B, as seen in Fig. 2 of the drawings. The base of the chamber or cylinder B forms the seat E for the valve, and is formed with the port F, substantially as shown in the drawings. (See Fig. 2.) This port is made smaller in its diameter than the diameter of the chamber or cylinder, in order that the liquid-pressure on the piston-head in the latter may prevail after the power is removed from the lever and then retain the valve on its seat when closed.

The tests to which I have submitted my invention seem to establish the course of operation to be, that as the liquid from the pipe is forced through the barrel of the faucet it fills the water-way below the valve-seat and valve, and in its upward course fills the chamber above the piston-head, and by preponderance of pressure on the face of the piston-head forces the connected valve down on the seat and retains it there, subject to be lifted by pressure on the handle of the lever, and returned to its seat, when the pressure on the lever is removed, by hydrostatic pressure on the surface of the piston-head in the chamber or cylinder.

I reserve the right to vary the construction of the parts without departing from the spirit of my invention.

What I claim as my invention, and desire to 5 secure by Letters Patent, is—

1. The combination, with a faucet-barrel having a formed chamber above the valve-seat and an induction-passage partially surrounding the said chamber, of a valve-rod with a 10 piston-head closed by the liquid-pressure applied above the piston-head, substantially as described.

2. The combination, with the faucet-barrel having a valve-seat, cylinder, and induction- 15 passage leading into the cylinder, of the self-closing valve consisting of the piston-rod, valve, piston-head, and pivoted lever, substantially as described.

In testimony whereof I affix my signature in presence of two witnesses.

JOSEPH E. MOONEY.
